UNITED STATES PATENT OFFICE

WARREN B. FLANDERS, OF PHILADELPHIA, PENNSYLVANIA, ASSIGNOR TO WESTINGHOUSE ELECTRIC & MANUFACTURING COMPANY, A CORPORATION OF PENNSYLVANIA

GOVERNING MECHANISM FOR MARINE POWER PLANTS

Application filed May 21, 1931. Serial No. 539,083.

My invention relates to a control mechanism for the ahead and astern admission valves of a reversible prime mover, and it has for its object to provide improved apparatus 5 of the character set forth.

A more particular object is to provide a control mechanism which is operative, upon movement of the control lever from ahead position to astern position, to open fully the 10 astern admission valve for the purpose of breaking the ahead speed, to maintain the valve open for acceleration in astern direction until a predetermined speed is attained, and then to move the valve in closing direction, 15 and which mechanism will operate in a similar manner to open the ahead admission valve upon shifting the control lever from astern position to ahead position.

It has already been proposed, in connection 20 with a reversible prime mover such as a steam turbine, upon reversing the direction of operation, to admit motive fluid for the purpose of breaking the speed of the prime mover in one direction and then to admit further motive fluid for acceleration in the 25 opposite direction. It has also been proposed to admit such motive fluid under control of a speed responsive governor. Ordinary governing mechanism, however, responds alike to speed in either direction and would be late, therefore, in admitting steam 30 for braking the speed of the prime mover in the direction in which it has been operating.

In accordance with my invention, I overcome 35 this difficulty by providing a mechanism which is operative, upon moving the control member from ahead to astern position, for releasing the astern admission valve from the action of the speed responsive governor; the mechanism being arranged, however, to restore the effectiveness of the governor as the prime mover slows down, so that the admission will be controlled by the governor 40 after speed in astern direction has been attained. The ahead valve is similarly operated upon shifting the control member from astern to ahead position.

The above and other objects are effected by 50 my invention as will be apparent from the following description and claims, taken in

connection with the accompanying drawings, forming a part of this application, in which:

Fig. 1 is a diagrammatic view showing the control mechanism applied to a low pressure turbine associated with a reciprocating engine 55 in a marine propulsion arrangement; and

Figs. 2 and 3 are sectional, diagrammatic views showing modified forms of valve-operating mechanism that may be substituted in the apparatus shown in Fig. 1. 60

Referring now more particularly to the drawings in detail, I show, in Fig. 1, a reciprocating engine 10 connected to a propeller shaft 11, on which a propeller 12 is mounted. A steam turbine 13, comprising an ahead section 14 and an astern section 15 is also connected to the shaft 11 through reduction gearing 16. The engine 10 is supplied with high pressure steam from any suitable source through a conduit 17 and a hand operated 70 admission valve 18. The engine exhausts into a receiver pipe 19, which communicates with a changeover valve 21, which in turn communicates with the ahead section 14 and with an exhaust connection 22 between the 75 turbine 13 and a condenser 23. In normal ahead operation, the exhaust from the reciprocating engine is conveyed to the ahead section 14, while during astern operation it is conveyed through the connection 22 to the 80 condenser 23.

In order to overcome the high inertia of the turbine to permit quick reversal of the turbine, it is desirable to admit high pressure steam for braking the speed of the turbine 85 in the direction in which it has been operating and to accelerate the speed in the opposite direction. High pressure steam for the ahead section 14 is supplied from any suitable source through a conduit 24, and its admission to the ahead section is controlled by a valve 25. It is also adapted to be cut off by a manually operated valve 26. High pressure steam for the astern section is supplied through a conduit 27, and its admission to the 90 astern section is controlled by a valve 28. It may also be shut off by a manually operated valve 29.

The reciprocating engine is provided with 100 any suitable form of reversing mechanism,

such as shown at 31. On the drawings, which are diagrammatic, the reversing mechanism has been shifted from its correct position with respect to the engine in order to show 5 its operative relation to the control mechanism hereafter described. The reversing mechanism is controlled by an engine reversing lever 32 fulcrumed at 33, which is connected thereto by a link 34, a bell crank lever 10 35 and a link 36.

To facilitate control of the apparatus, the valves controlling admission of motive fluid to the turbine are controlled by the engine reversing lever 32. The change-over valve 21 15 is actuated by a servo-motor 37 which includes a piston 38 connected to the valve and operating in a cylinder 39. A spring 41 biases the piston 38 to the left. The servo-motor 37 is controlled by a pilot valve 42, 20 which is connected to the reversing lever 32 and operates in a casing 43. The casing 43 is formed with two ports 44 and 45, which communicate with the left-hand end and the right-hand end of the cylinder 38, respectively, 25 through conduits 46 and 47. A central port 48 communicates through a conduit 49 with any suitable source of fluid pressure, for example, a governor pump 51 driven by the turbine. The end portions of the casing 43 30 communicate with an exhaust conduit 52.

The ahead admission valve 25 is controlled by a servo-motor 53 which includes a piston 54 connected to the valve and operating in a cylinder 55. A spring 56 biases the piston in 35 valve-closing direction.

The servo-motor 53 is controlled by a relay valve 57 disposed in a casing 58, the latter having a port 59 which communicates through a conduit 61 with the lower end portion 40 of the cylinder 55. The casing is provided with an exhaust port 62 disposed above the port 59 and with a pressure supply port 63, disposed below the port 59 and communicating with the pressure supply conduit 49. 45 The pilot valve 57 is formed with piston portions 64, 65 and 66, which are adapted to place the port 59 in communication with either the exhaust port 62 or the fluid supply port 63.

50 The pilot valve 57 is connected to and is adapted to be actuated by the reversing lever 32. It is connected through a link 67 to the horizontal arm of a bell crank lever 68. The vertical arm of the bell crank lever is connected through a two-part rod 69 to the lever 32. The part connected to the lever 32 has a tubular portion 71 in which there is telescoped a stem 72 integral with the part of the rod connected to the bell crank lever 68. 55 The two parts of the rod are drawn toward 60 each other by a tension spring 73.

A governing mechanism 74 is provided in order to effect closing of the ahead high pressure admission valve 25 when the turbine has 65 obtained sufficient speed in ahead direction.

Any suitable form of speed responsive governing mechanism may be employed, the mechanism shown being of the hydraulic type. It includes a piston 75 disposed in a cylinder 76 and biased upwardly by a spring 77. The piston is biased downwardly by fluid pressure varying as the square of the speed of the turbine, in this case provided by the governor pump 51, conveyed through the conduit 49 and admitted to the upper portion of the cylinder 76. A piston rod 78 extends downwardly through the lower end of the cylinder and carries a collar 79 which is bevelled on its upper edge. 70 75

A vertical link 81 is pivoted to the horizontal arm of the bell crank lever 68 and carries a tooth 82. The governing mechanism 74 is so arranged that the collar 79 is adapted to engage the tooth 82 upon sufficient downward movement of the collar in response to increase in speed. The link 81 is adapted to be moved to the left to disengage the collar 79 from the tooth 82 by a link 83. The left-hand end of the link 83 is connected to a lever 84 fulcrumed at 85. 80 85

The lever 84 includes a projection 86 constituting a stop member which abuts against a stationary part to limit the clockwise movement of the lever 84 about its fulcrum. A lever 87 is pivoted to the upper end of the lever 84 and carries a stop 88. The latter is adapted to abut the lever 84 to limit counterclockwise movement of the lever 87 relative to the lever 84 and about its pivotal connection therewith. The lower end of the lever 87 is connected to a tension spring 89 which biases the same to the right, and which also biases the lever 84 to the right through the lever 87. The lever 87 carries a tooth 91 90 95 extending upwardly and adapted to be engaged by a finger 92 carried on the part of the rod 69 connected to the reversing lever 32. 100 105

The astern high pressure admission valve 28 is operated by a servo-motor 53' which is identical with the servo-motor 53, and which is controlled through a conduit 61' by a pilot valve 57', the latter being identical with the pilot valve 57. The pilot valve 57' is connected to the reversing lever 32 by mechanism which is identical with the mechanism connecting the pilot valve 57 to the reversing lever, but which is oppositely arranged, with respect to right and left, so that movement in a given direction of the reversing lever 32 will cause movement of the pilot valves 57 and 57' in opposite directions. These parts bear the same reference numerals with the prime mark (') affixed. The tooth 82' is likewise adapted to be engaged by a collar 79' of a governing mechanism 74', which is controlled by fluid pressure conveyed through the conduit 49 to respond to the speed of the turbine 13. 110 115 120 125

The operation of the above described apparatus is as follows: 130

Assume the apparatus to be in shut down position as shown on the drawings, in which position the pilot valves 57 and 57' place the ports 59 and 59' in communication with the exhaust ports 62 and 62' respectively. Operating fluid is accordingly exhausted from the servo-motors 53 and 53' and the springs therein bias the pistons to maintain the high pressure admission valves 25 and 28 in fully closed position.

Assume now that it is desired to begin operation in ahead direction. The handle of the reversing lever 32 is moved to the left to the ahead position, thereby shifting the reversing mechanism 31 to the position providing ahead operation of the reciprocating engine 10. The valve 18 is then opened to admit high pressure steam to the engine. The movement of the reversing lever 32 moves the pilot valve 42 to the right admitting fluid pressure through the conduit 47 to the right hand end of the servo-motor 37. The latter moves the changeover valve 21 to the position conveying the exhaust from the engine to the ahead section of the turbine.

The movement of the reversing lever 32 to the left moves the pilot valve 57' downwardly through the rod 69' and the bell crank lever 68'. The pilot valve 57' maintains the port 59 in communication with the exhaust port 62' and the astern admission valve 28 remains shut. The lever 32 also moves the pilot valve 57 upwardly through the rod 69 and the bell crank lever 68. The movement of the rod 69 to the left also causes the finger 92 to engage the tooth 91. This action, which does not have any effect on the operation of the mechanism when starting from shut-down, will be described later. The pilot valve 57 in the upper position places the port 59 in communication with the pressure supply port 63, admitting fluid pressure to the servo-motor 53 and causing the latter to open the ahead admission valve 25.

The high pressure steam admitted by the valve 25 assists the exhaust steam from the reciprocating engine to more quickly accelerate the speed of the turbine in ahead direction, reducing the time required to bring the turbine and engine to full speed. As more economical operation is effected by using only exhaust steam in the turbine, it is desirable to cut off the high pressure steam to the turbine when full speed is approached. This may be done at any partial speed such as one-half speed or three-quarter speed. The piston 75 of the governing mechanism 74 moves downwardly under force of the increasing fluid pressure developed by the pump 51. The collar 78 moves into engagement with the tooth 82 and moves the bell crank lever 68 in clockwise direction against the force of the spring 73. As the desired predetermined speed is attained, the piston portion 65 of the pilot valve 57 passes the

port 59 and places the same in communication with the exhaust port 62. Fluid pressure is exhausted from the servo-motor 53, the spring 56 of which shuts the valve 25. The turbine then continues to operate on partially expanded steam exhausted from the reciprocating engine.

Assume now that it is desired to reverse from ahead operation to astern operation. The valve 18 is closed, the reversing lever 32 shifted to the right from ahead to astern position, and the valve 18 is reopened. The movement of the reversing lever shifts the reversing mechanism 31 to the position providing operation of the engine in astern direction. It also moves the pilot valve 42 to the left, admitting fluid pressure to the left-hand end of the servo-motor 37 and exhausting fluid from the right hand end. The servo-motor 37 moves the changeover valve 21 to the right, admitting the exhaust from the reciprocating engine to the condenser 23 through the connection 22.

The movement of the reversing lever 32 to the right also moves the rod 69 and the adjacent part of the rod 69 to the right. The pilot valve 57 being already held in lowermost position by the governing mechanism 74, this movement, so far as the rod 69 is concerned, merely serves to telescope the parts 71 and 72 and to take up the deflection of the spring 73. The finger 92 engages the tooth 91, but the latter returns to its normal position under force of the spring 89 as soon as the finger 92 has passed.

As the lever 32 begins movement from ahead position to astern position, it tends to move the pilot valve 57' upwardly through the extensible rod 69' and the bell crank lever 68'. Upward movement of the pilot valve 57' during the first part of the movement is prevented by the engagement of the collar 79' with the tooth 82', said collar being in lowermost position due to full speed of the turbine in ahead direction. Consequently, as the lever 32 moves to the right, the rod 69' and the spring 73 are extended.

As the lever 32 moves beyond the neutral position, the finger 92' comes into engagement with the tooth 91'. Due to the abutment of the stop 88' against the lever 84', the levers 87' and 84' are moved to the right as a unit, and move the link 83' to the right. The tooth 82' is drawn out of engagement with the collar 79', permitting the spring 73' to move the pilot valve 57' upwardly through the bell crank lever 68', taking up the lost motion in the rod 69'. When the finger 92' has passed the tooth 91' the spring 89' returns the levers 87' and 84' to the left. The pilot valve 57' then continues to move upwardly as the movement of the lever 32 to astern position is completed.

The pilot valve 57' admits fluid pressure to the servo-motor 53' which thereby moves

the astern admission valve 28 to full open position. The high pressure steam admitted to the astern section of the turbine begins at once to brake the ahead speed of the turbine.

As the ahead speed decreases, the governing mechanism 74' moves the collar 79' upwardly, and as it approaches its uppermost position, the surface engages the lower inclined surface of the tooth 82', forcing the link 81' to the right. As it passes the upper edge of the tooth 82', the spring 89' moves the link 81' to the left, placing the tooth 82' in engageable relation with respect to the collar 79', so that as the speed in the astern direction begins to increase the tooth 82' is moved downwardly by the collar 79'. As a predetermined speed is attained, the pilot valve 57' effects closing of the pilot valve 28.

Upon shifting the reversing lever 32 from astern position to ahead position, the mechanism will operate in a manner similar to that just described to open the ahead high pressure admission valve 25.

In the above described embodiment, the pilot valves 57 and 57' cause the pistons of the servo-motors to be moved throughout their entire travel at one time. In Fig. 2, I show a modified form of servo-motor which moves the high pressure admission valve incrementally through its travel in response to increase in speed through a limited range. The servo-motor includes a piston 94 connected to the high pressure admission valve 28 and operating in a cylinder 95. A spring 96 biases the piston 94 in closing direction and serves to close the valve 28 when the apparatus is shut down. The servo-motor is controlled by a pilot valve 97 disposed in a casing 98. Passages 99 and 101 provide communication between the pilot valve casing and the upper and lower ends of the cylinder 95 and are normally covered by piston portions 103 and 104 of the pilot valve. The pilot valve casing is also provided with fluid pressure supply ports 105 and 106 and a fluid discharge port 107. A floating lever 108 is connected at its ends to the operating piston 94 and pilot valve 97 and intermediate its ends to the bell crank lever 68' through the link 67'.

The operation of this mechanism is as follows:

Upon clockwise movement of the bell crank lever 68', the pilot valve 97 is moved upwardly. Fluid pressure is admitted to the lower end of the cylinder 95 and exhausted from the upper end, moving the piston 94 upwardly and providing opening movement of the valve 28. After the piston 94 moves upwardly, it tilts the lever 108 about the pivotal connection with the link 67' and returns the pilot valve 97 to cut off position.

Upon movement of the bell crank lever 68' in counter-clockwise direction, the pilot valve 97 is moved downwardly. Fluid pressure is admitted to the upper end of the cylinder 95

and exhausted from the lower end, moving the piston 94 downward. In this case, a movement of the valve 28 in closing direction is provided. Downward movement of the piston 94, through the lever 108, returns the pilot valve 97 to cut off position.

This valve operating mechanism may be substituted for either or both of the servomotors 53 and 53' and the pilot valves 57 and 57'. The operation of the mechanism as a whole is the same, the only difference being that as the speed of the turbine increases, the admission valve is opened incrementally through a small range of speed, instead of being moved throughout its full travel as the speed increases beyond a single predetermined point.

In Fig. 3 is shown a still further modified form of valve operating mechanism. This mechanism is similar to that of Fig. 2 in that it operates through a limited range of speed. It includes a pressure device 109 providing a fluid pressure varying as a function of the position of the bell crank lever 68', said lever being moved by the governing mechanism 74' in accordance with the speed of the turbine. The pressure device 109 includes a sleeve 111, disposed in a casing 110 and connected through the link 67' to the bell crank lever 68', and having a fluid admission port 112 and a fluid exhaust port 113. Disposed within the sleeve 111 is an inner sleeve 114, which has fluid admission ports 115 and fluid exhaust ports 116, which are disposed adjacent to the ports 112 and 113, respectively, and intermediate said two groups of ports, as will be more apparent from Fig. 3 of the drawings.

The interior of the inner sleeve 114 is in communication, through the lower end of the casing 110 and a conduit 118, with the lower end of the cylinder 55' of the servo-motor 53'. The sleeve 114 is closed at its upper end, and a spring 117 is connected to the sleeve and to the casing 110 to bias the sleeve downwardly. The sleeve 114 is biased upwardly against the force of the spring 117 by the fluid pressure within its interior and in the lower end of the casing 110. Accordingly, the sleeve 114 is moved up and down by variations in fluid pressure, assuming a position which is a function of the pressure.

The operation of this mechanism is as follows:

Upon downward movement of the sleeve 111, such as caused by downward movement of the governing mechanism 74' in response to increase in speed, the exhaust ports 113 and 116 are placed in communication, permitting discharge of fluid from the interior of the sleeve 114. The pressure thereof decreases until the spring 117 moves the inner sleeve 114 downwardly to cut-off position. In response to this decrease in pres-

sure, the spring 56' of the servo-motor 53' moves the valve 28 in closing direction a distance proportional to the decrease in fluid pressure.

5 Upon upward movement of the sleeve 111, such as caused by upward movement of the governing mechanism 74' in response to decrease in speed, the ports 112 and 115 are placed in communication. Fluid under 10 pressure is admitted to the interior of the inner sleeve 114 and increases the pressure of the fluid therein until the inner sleeve 114 moves upwardly to cut off further admission of fluid. In response to the increased 15 fluid pressure, the piston 54' of the governor 53' moves the valve 28 in opening direction.

From the above description, it will be seen that I have provided a mechanism in which 20 the valve closing action of the governing mechanism is overcome, in response to shifting of the reversing lever, during braking of the turbine speed in the direction in which it has been operating.

25 While I have shown my invention in but one form, it will be obvious to those skilled in the art that it is not so limited, but is susceptible of various changes and modifications, without departing from the spirit 30 thereof, and I desire, therefore, that only such limitations shall be placed thereupon as are imposed by the prior art or as are specifically set forth in the appended claims.

What I claim is:

35 1. The combination with a reversible prime mover having an ahead and an astern admission valve, of a control mechanism for the valves comprising means including and controlled by a control member for opening 40 either of said admission valves, means responsive to the speed of the prime mover for effecting closing movement of each valve in response to increase in speed of the prime mover, and means for releasing either admission valve from the control of the speed- 45 responsive means upon movement of the control member to the position calling for opening of the valve, and means for restoring said control upon slowing down of the prime 50 mover to a predetermined speed.

2. The combination with a reversible prime mover having an ahead and an astern admission valve, of a control mechanism for the valves comprising a control member adapted 55 to be positioned for ahead operation or astern operation, valve-operating mechanism adapted to be controlled by said control member for each of the admission valves, means responsive to the speed of the prime mover and 60 adapted to cause each valve operating mechanism to operate in valve-closing direction upon predetermined increase in speed, and means for releasing the ahead valve-operating mechanism from the control of the speed- 65 responsive means upon movement of the con-

trol member from astern to ahead position and for releasing the astern valve-operating mechanism from the control of the speed-responsive means upon movement of the control member from ahead to astern position. 70

3. The combination with a reversible prime mover having an ahead and an astern admission valve, of a control mechanism for the valves comprising a control member adapted to be positioned for ahead operation or astern 75 operation, valve-operating mechanism adapted to be controlled by said control member for each of the admission valves, means responsive to the speed of the prime mover and adapted to cause each valve operating mechanism to operate in valve-closing direction 80 upon predetermined increase in speed, means for releasing the ahead valve-operating mechanism from the control of the speed-responsive means upon movement of the control 85 member from astern to ahead position and for releasing the astern valve-operating mechanism from the control of the speed-responsive means upon movement of the control member from ahead to astern position, and 90 means for restoring the control of the speed-responsive means upon decrease in the speed of the prime mover to a predetermined low speed. 95

4. The combination with a reversible prime mover having an ahead and an astern admission valve, of a control mechanism for said valves comprising a control member movable to ahead, astern and neutral positions, means for operating the admission valves in accordance with the position of the control member, means responsive to a predetermined speed of the prime mover for causing closing movement of the valves against the action of the control member, means for releasing the action of the speed-responsive means on either valve upon movement of the control member from neutral position to the position calling for opening of the valve, and means for reestablishing the effectiveness of the speed responsive means upon sufficient decrease in speed of the prime mover, whereby upon movement of the control member to ahead or astern position, the admission valve corresponding to the position of the control member is opened until the speed of the prime mover has decreased and thereafter again increased. 105

5. The combination with a reversible prime mover having an ahead admission valve and an astern admission valve, of a control mechanism for said valves comprising speed-responsive means for effecting closing of said valves in response to increase above a predetermined speed, control means including a control member for causing opening of either of said valves, and means for disengaging the speed-responsive means from either valve when the control member is moved to the position calling for opening of that valve and for 110 115 120 125 130

restoring the speed-responsive means to control of the valve when the speed of the prime mover decreases to a predetermined low speed.

6. The combination with a reversible prime mover having an ahead and an astern admission valve, of a control mechanism for said valves comprising a control member movable to positions calling for ahead and astern operation of the prime mover and to neutral position, and a valve operating mechanism for each admission valve adapted to move the admission valve in opening or closing direction as dictated by the position of the control member, speed-responsive means movable upon increase in speed into engaging relation with a controlling part of each valve-operating mechanism to effect closing movement of the admission valve operated thereby upon sufficient increase in speed, means responsive to movement of the control member from neutral position to ahead or astern position for temporarily bringing the controlling part of the corresponding valve-operating mechanism out of engageable relation with the speed-responsive means, said speed-responsive means snapping into engageable relation with said part upon sufficient decrease in speed so that upon subsequent increase in speed to a predetermined speed, the valve operating mechanism will move the valve in closing direction.

In testimony whereof, I have hereunto subscribed my name this 19th day of May, 1931.
